HALO DERIVATIVES OF BENZOYL LEUCO METHYLENE BLUE

Clyde S. Adams, Yellow Springs, Marjorie J. Cormack, Dayton, and Mary Lou Frazier, Springfield, Ohio, assignors to The National Cash Register Company, Dayton, Ohio, a corporation of Maryland

No Drawing. Application October 27, 1955,
Serial No. 543,266

8 Claims. (Cl. 260—243)

This invention relates to the substantially light-stable halogenated derivatives of the leucomethylene blue compound 10-benzoyl-3,7-bis(dimethylamino)phenothiazine, having the general structure

where R is taken from the group consisting of chlorine and bromine, and where N is a number from 1 to 5.

This is a continuation-in-part of our application Serial No. 518,334, filed June 27, 1955, now abandoned.

The known unhalogenated leuco compound 10-benzoyl-3,7-bis(dimethylamino)phenothiazine, also known as benzoyl leucomethylene blue, normally is substantially colorless and has been used as a color reactant which turns to a blue-green color on prolonged contact with acid clay-like materials such as attapulgite and halloysite. It is used in conjunction with other, faster-reacting, colorless color-reactants, also turned to the colored form on contact with such acid clay-like materials.

One of the present primary uses of these color-reactant materials in their incorporation in transfer coatings on the rear surfaces of manifold record sheets. When these manifold sheets are placed over paper sensitized with attapulgite or halloysite, and an impression, by printing or writing, is made, transferring the color reactants to the sensitized surfaces of the under sheets, impressions in color are made thereon. One type of manifold sheet having a transfer coating of the type described is disclosed in United States Patent No. 2,646,367, which issued, on the application of Chester Davis and Ned A. Thatcher, on July 21, 1953. In that patent there is disclosed a base web of paper having a coating made of wax and oil, the oil having dissolved therein a fast-reacting colorless color reactant—namely, crystal violet lactone—which is more specifically described as 3,3-bis(p-dimethylamino-phenyl)-6-dimethylamino phthalide, which turns to a dark blue color upon coming into contact with attapulgite or halloysite, and the slower-reacting compound 10-benzoyl-3,7-bis(dimethylamino)phenothiazine, which was mentioned before. The crystal violet lactone color fades after prolonged exposure to light, and, as it gradually fades away, the slower-reacting 10-benzoyl-3,7-bis(dimethylamino)phenothiazine gradually develops color, so that the printing or writing is not lost. Another such manifold sheet is one in which the transfer coating is composed of oil-containing, pressure-rupturable microscopic capsules of gelled hydrophilic colloid material, and in which the encapsulated oil carries the color reactants of the first mentioned patent, and it is disclosed in United

2

States Patent No. 2,712,507, which issued, on the application of Barrett K. Green, on July 5, 1955.

One drawback to the use of 10-benzoyl-3,7-bis(dimethylamino)phenothiazine is that it gradually decomposes to the colored form on exposure to light. Thus, if the side of a transfer sheet which is coated with the transferable material is exposed to light, it gradually assumes an undesirable blue-green color. The halogenation of the 10-benzoyl-3,7-bis(dimethylamino)phenothiazine, with either chlorine or bromine, almost completely prevents this.

Therefore, it is the object of this invention to provide essentially light-stable halogenated derivatives of 10-benzoyl-3,7-bis(dimethylamino)phenothiazine.

These halogenated derivatives may be made by reacting the zinc chloride double salt of leucomethylene blue, having the structure

with the proper halobenzoyl chloride.

As a first instance, suppose that it is desired to make 10-(o-chlorobenzoyl)-3,7-bis(dimethylamino)-phenothiazine, having the following structure:

To 73 grams (0.146 mole) of the zinc chloride double salt of leucomethylene blue is added 122 grams (1.55 moles) of pyridine in a round-bottom, three-necked flask fitted with a stirrer, a thermometer, and a dropping funnel. After this has been heated to 90 degrees centigrade, and while it is being stirred, 50 grams (0.284 mole) of o-chlorobenzoyl chloride is added, drop by drop, after which the dropping funnel is replaced by a reflux condenser, and the mixture is gently refluxed for one and one half hours.

The reaction mixture then is poured into water, whereupon a semi-solid material precipitates out. The water is decanted off, and the solid residue is mixed with 48 grams of sodium hydroxide dissolved in one liter of water. This mixture is stirred and warmed for one half hour. The alkaline fluid is decanted off, and the remaining solid residue is washed with water. The washed residue is extracted with two liters of hot benzene. The resulting dark benzene solution then is treated with fuller's earth and filtered.

The filtrate is concentrated to 600 milliliters, cooled to room temperature, and the reaction product is precipitated out with petroleum ether.

The final product is a white crystalline material.

The m-chloro and the p-chloro derivatives may be manufactured by the same process, using, in place of the o-chlorobenzoyl chloride, the m-chlorobenzoyl chloride and the p-chlorobenzoyl chloride, respectively, in the same molecular proportions.

The various dichloro, trichloro, tetrachloro, and pentachloro derivatives may be made in the same manner by using the proper chlorinated benzoyl chloride.

By using 2,3-dichlorobenzoyl chloride and reacting it with the zinc chloride double salt of leucomethylene blue,

3

the product obtained is 10-(2,3-dichlorobenzoyl)-3,7-bis(dimethylamino)phenothiazine; similarly, using the 2,4-dichlorobenzoyl chloride the product obtained is 10-(2,4-dichlorobenzoyl)-3,7-bis(dimethylamino)phenothiazine; using the 2,5-dichlorobenzoyl chloride the product obtained is 10-(2,5-dichlorobenzoyl)-3,7-bis(dimethylamino)phenothiazine; using the 2,6-dichlorobenzoyl chloride the product obtained is 10-(2,6-dichlorobenzoyl)-3,7-bis(dimethylamino)phenothiazine; using the 3,4-dichlorobenzoyl chloride the product is 10-(3,4-dichlorobenzoyl)-3,7-bis(dimethylamino)phenothiazine; and using the 3,5-dichlorobenzoyl chloride the product obtained is 10-(3,5-dichlorobenzoyl)-3,7-bis(dimethylamino)phenothiazine. The ingredients are used in the same molecular proportions as first given in connection with the making of 10-(o-chlorobenzoyl)-3,7-bis(dimethylamino)phenothiazine.

By using the selected tetrachloro benzoyl chloride, the corresponding 10-(tetrachlorobenzoyl)-3,7-bis(dimethylamino)phenothiazine is produced; and by using pentachlorobenzoyl chloride, 10-(pentachlorobenzoyl)-3,7-bis(dimethylamino)phenothiazine is produced.

Brominated benzoyl chlorides may be used in place of the chlorinated benzoyl chlorides to make the bromo derivatives. Thus, if it is desired to make 10-(o-bromobenzoyl)-3,7-bis(dimethylamino)phenothiazine, the zinc chloride double salt of leucomethylene blue would be reacted with o-bromobenzoyl chloride in the same molecular proportions as set forth in connection with the making of the chloro derivatives.

In the foregoing examples, selected known halogenated benzoyl chlorides have been used to react with the zinc chloride double salt of leucomethylene blue.

A cheaper product may be made by halogenating benzoyl chloride by passing the selected halogen gas through the benzoyl chloride in the presence of a catalyst. This will result in a mixture of halogenated benzoyl chlorides as a consequence of the random attachment of the halogen atoms on the benzene ring. The degree of halogenation may be determined by weighing the benzoyl chloride before and after passing the halogen gas through it. Generally speaking, the degree of halogenation estimated by this method is a practical one and not an absolute one; that is to say, if enough halogen gas is combined with the benzoyl chloride, so that in theory each benzoyl chloride molecule could have two halogen atoms thereon, the chances are that in the mixture most of the benzoyl chloride molecules would have two chlorine atoms thereon, and the reaction product would essentially be a mixture of dichlorobenzoyl chloride, the exact positions of the chlorine atoms on the benzene ring not being known.

An example will now be given of the process for making a mixture of dichlorobenzoyl chlorides:

A blackened three-necked one-liter flask, equipped with a below-the-liquid-surface glass inlet tube, stirrer, thermometer, and outlet to a hydrogen chloride adsorber, is charged with

420 grams (3 moles) of technical benzoyl chloride,
3 grams of iodine, and
2 grams of iron.

The system is weighed and heated to 40-45 degrees centigrade. Chlorine is passed in at this temperature range for three hours until approximately 210 grams of chlorine has been adsorbed. The resulting oil is blown with dry air for one half hour to remove any remaining hydrogen chloride and unreacted chlorine. The final net weight gain in the system is 207 grams, which is the theoretical gain.

In making mixed trichlorobenzoyl chlorides, the same apparatus and charge are used except that the chlorination is continued for four hours at the same temperature range. After blowing with dry air, a net weight gain of 287 grams was noted, which is 95 percent of the theoretical gain, which is 310 grams.

4

These mixtures of halogenated benzoyl chloride are then condensed with the zinc chloride salt of methylene blue as previously described, providing a mixture that has characteristics equivalent to the more specific compounds.

5 What is claimed is:

1. The compound 10-(halobenzoyl)-3,7-bis(dimethylamino) phenothiazine, having the structure

where R is taken from the group consisting of chlorine and bromine, and where N is a number from 1 to 5.

20 2. The compound 10-(chlorobenzoyl)-3,7-bis(dimethylamino) phenothiazine, having the structure

where N is a number from 1 to 5.

30 3. The compound 10-(bromobenzoyl)-3,7-bis(dimethylamino) phenothiazine, having the structure

40 where N is a number from 1 to 5.

45 4. The compound 10-(m-chlorobenzoyl)-3,7-bis(dimethylamino) phenothiazine having the structure

50 5. The compound 10-(2,4-dichlorobenzoyl)-3,7-bis(dimethylamino) phenothiazine having the structure

5

6. The compound 10 - (3,4-dichlorobenzoyl)-3,7-bis-(dimethylamino) phenothiazine, having the structure

5

6

8. The compound 10-(m-bromobenzoyl)-3,7-bis-(dimethylamino) phenothiazine, having the structure

10

7. The compound 10 - (p-chlorobenzoyl)-3,7-bis-(dimethylamino) phenothiazine, having the structure
